US00D932095S

(12) United States Design Patent (10) Patent No.: US D932,095 S
Liu (45) Date of Patent: * Sep. 28, 2021

(54) ELECTRONIC CIGARETTE

(71) Applicant: Tuanfang Liu, Shenzhen (CN)

(72) Inventor: Tuanfang Liu, Shenzhen (CN)

() Term: 15 Years

(21) Appl. No.: 29/724,127

(22) Filed: Feb. 12, 2020

(30) Foreign Application Priority Data

Aug. 27, 2019 (CN) 201930468435.2

(51) LOC (13) Cl. 27-02

(52) U.S. Cl.

USPC D27/162

(58) Field of Classification Search

USPC D27/100, 101, 162, 163, 164, 165, 166, D27/167, 168, 169, 170, 171, 172, 173, D27/174, 175, 176, 177, 178, 179, 180, D27/181, 182, 183, 184, 185, 186, 187, D27/188, 189, 190, 191, 192, 193; D28/91.1; D23/360, 362; D24/110, D24/110.4, 110.5, 110.6, 113

(57) CLAIM

The ornamental design for an electronic cigarette, as shown and described.

DESCRIPTION

FIG. 1 is a front elevation view of an electronic cigarette; FIG. 2 is a rear elevation view thereof; FIG. 3 is a left-side elevation view thereof; FIG. 4 is a right-side elevation view thereof; FIG. 5 is a top plan view thereof; FIG. 6 is a bottom plan view thereof; FIG. 7 is a perspective view thereof; and, FIG. 8 is a bottom perspective view thereof. The broken lines in the drawings depict portions of the electronic cigarette that form no part of the claimed design.

1 Claim, 8 Drawing Sheets
